UNITED STATES PATENT OFFICE.

ALBERT B. UPTON, OF HIGHLAND PARK, MICHIGAN.

PORTABLE FRAME FOR TENTS.

1,204,616.

Specification of Letters Patent. Patented Nov. 14, 1916.

Application filed September 13, 1915. Serial No. 50,321.

To all whom it may concern:

Be it known that I, ALBERT B. UPTON, a citizen of the United States of America, residing at Highland Park, in the county of Wayne and State of Michigan, have invented certain new and useful Improvements in Portable Frames for Tents, &c., of which the following is a specification, reference being had therein to the accompanying drawings.

10 This invention relates to a frame that is adaptable for use as a merry-go-round, a clothes reel, a frame for a portable house or for a tent, and to disposition of parts that makes dismounting of the device for shipping, extremely easy, lightens and stiffens the construction and minimizes the holding members.

15 The invention consists in the matters hereinafter set forth and more particularly pointed out in the appended claims.

20 In the drawings, Figure 1 is a view in perspective of a frame that embodies features of the invention arranged for a merry-go-round; Fig. 2 is a view of a slight modification of the frame whereby it becomes available as a tent; Fig. 3 is a view in perspective of the modification with an applied covering; Fig. 4 is a view in detail of the connection of a center post and the arm braces thereof, and Fig. 5 is a view in detail of a pivot joint.

25 Referring to the drawings, a center post 1 that is cylindrical and preferably made of tubing, is in the form shown in Figs. 1 and 5, provided with a telescoping rotatable upper section 2. A flanged bearing head 3 that is inserted in the stationary section of the post bears against the under slightly dished 30 or recessed face of a bearing block 4 that is prevented from upward movement in the section 2 by the inner end portions of brace bolts 5. The slotted heads 6 of the latter receive arms 7 of strap iron or the like, with 35 pivot bolts 8 securing each in place.

40 The upper end of the center post has a plurality of longitudinal slots 9 indicated plainly in Fig. 4, corresponding in section and alinement to the holding bolts 5. A V-shaped brace for each arm, such as indicated at 10, has the upper end portion pinched together or compressed as indicated at 11, to drop into the companion slot 9 while its outer end is slotted or bifurcated and is 45 maintained in position on the arm which it embraces by a suitable pivot pin 12. A cap

13 may be used to cover and act as a collar around the slotted end portion of the post. A flexible connection or stay member 14 passes through suitable perforations in the 50 outer end portion of the arm 7, which are preferably provided with a series of such apertures.

55 In assembling the parts, after shipment, the arms 7 are connected by the bolts or cross pins 8 to the holding bolts 5 and the braces 10 are dropped into position and pinned to the arms 7 by the cross pin 12. The flexible connection or stay member 14 has previously been passed through the apertures and when the arms are extended the adjustment is such that there is strain put upon the flexible connection which thereby cooperates with the braces 10 to hold the 60 parts in rigid extended position.

70 As a result a frame is obtained that is adaptable for use as a merry-go-round, as a clothes reel or a portable house or tent, the rigidity of the structure permitting the use of hanging bunks or the placing of other 75 devices in suspension from the frame. As it is extremely easy to ship, when collapsed, it is found to be of particular advantage for contractors, harvesters or the like to furnish 80 temporary quarters for their crews.

85 Obviously, changes in the details of construction may be made without departing from the spirit of the invention but I do not care to limit myself to any particular form or arrangement of parts.

90 What I claim is:—

95 1. A frame comprising a cylindrical hollow center post with longitudinal slots extending downwardly from the upper end thereof, holding bolts extending radially from the post below and in alinement each with a slot and having slotted heads, arms each pivoted at the inner end in the slotted head of a holding bolt, and flanged braces embracing the arms near the outer ends 100 thereof and interlocking near their inner ends each with a slot of the post.

105 2. A frame comprising a cylindrical center post the upper section of which has longitudinal slots extending downwardly from the upper end, brace bolts extending radially from the post each in line with a slot, and having a slotted head, arms pivotally secured at the inner ends in the slotted heads of the bolts, flanged brace members having 110 compressed portions near their upper ends that are adapted to drop into and interlock

with the slots of the post, the outer end portions of the braces being bifurcated to embrace the arms near the outer ends of the latter, pivot bolts connecting the arms and bifurcated ends of the braces, and means connecting the outer end portions of the arms to each other and cooperating with the braces to hold the same in extended position.

3. A frame comprising a tubular center post, the upper section of which has a longitudinally slotted upper end portion and a lower portion in telescopic engagement over the lower section of the post, a flanged bearing head seated in and on the lower section,

a bearing block in the upper section resting 15 on the bearing head, laterally extending brace bolts in the upper section against the inner portions of which the block bears upwardly, arms extending radially from the brace bolts, and braces pivoted to the arms 20 and interlocking each with a slot of the upper section of the post.

In testimony whereof I affix my signature in presence of two witnesses.

ALBERT B. UPTON.
